UNITED STATES PATENT OFFICE.

CHARLES E. BUELL, OF NEW HAVEN, CONNECTICUT.

ELECTRIC LIGHT FOR BURGLAR-ALARMS.

SPECIFICATION forming part of Letters Patent No. 232,678, dated September 28, 1880.

Application filed March 11, 1880. (No model.)

To all whom it may concern:

Be it known that I, CHARLES E. BUELL, of the city and county of New Haven, State of Connecticut, have made certain new and useful Improvements in Electrical Illumination, of which the following is a specification.

My invention relates to controlling electric lamps, and is applicable in dwellings, stores, banks, and other like places.

10 The object of my invention is to make electric lamps operative or bring them into action by means heretofore extraneous to electric lamps; and a further object of my invention is to combine electric lamps with electric alarms.

15 I accomplish the object of my invention by connecting the wires which are to convey the currents to illuminate the lamps with the windows and doors of an apartment, or with the door of a vault, or with concealed keys or analogous appliances in or about a vault, safe, or room to be protected against intrusion, by such means and in such a manner that the opening of such door or window will bring the desired lamps into action by closing a circuit normally

20 open or by rupturing a circuit which is normally closed, preferably the latter.

Figure 1 represents a simple form of key, composed of a spring, S, which, in its normal position, rests against the contact-piece C, 30 which completes a circuit through the wires f f, both the spring S and piece C being metal. The pin p is intended to be attached to a door or window, which, when closed, brings the pin p against the spring S, forcing it away from the piece C and against the point T, which is 35 a terminal of a branch circuit, to be described hereinafter.

Fig. 2 represents the parts shown in Fig. 1, and described as attached to the window W 40 and door D, both being represented as not fully closed.

Fig. 3 represents a main electric circuit, in which are interposed the electric lamps L L, and provided with the switch D², which is a 45 switch for changing the flow of the currents to charge the lamps, so that they will flow through wire f' and springs S S and wire h, around the lamps L L, which may be left turned on.

The raising of the window W or the opening of the door D serves to release the spring S, 50 which is held depressed while the door or window remains closed. The spring S, being released, comes into contact with piece C, putting the current through the lamps L L, over the wires f² f², making them luminous. 55

The resistance R can be placed in the wire h to make the circuit the same as the circuit containing the lamps in point of conductivity.

The resistance R may be any conducting resistance, or may be an electro-magnet used to 60 strike a bell or control any branch wire or actuate or control an alarm mechanism.

Any of the well-known appliances used to control burglar-alarms may be employed in place of the spring S and piece C, shown and 65 described for controlling electric lamps.

What I claim as new, and desire to secure by Letters Patent, is—

1. In a system of electric illumination, the combination, with a circuit-wire which includes 70 one or more electric lamps, of an auxiliary circuit-wire which includes circuit-changing keys controlled and operated by doors and windows, and means for switching the main circuit through or around the lamps. 75

2. In a system of electric illumination, the combination, with a circuit-wire which includes one or more electric lamps, of an auxiliary circuit-wire which is controlled and operated by doors and windows, and which is made equal 80 in conductivity to the circuit-wire which includes the lamps.

3. In a system of electric illumination, the combination, with a circuit-wire which includes one or more electric lamps, of an auxiliary circuit which includes an electro-magnet for controlling and actuating alarms and alarm-circuits, and means for automatically controlling said auxiliary circuit to make operative the lamps and alarms simultaneously. 85

CHARLES E. BUELL.
